UNITED STATES PATENT OFFICE.

O. W. BAYLEY, OF MANCHESTER, NEW HAMPSHIRE, ASSIGNOR TO THE MANCHESTER LOCOMOTIVE WORKS.

FURNACE FOR LOCOMOTIVES.

Specification of Letters Patent No. 12,749, dated April 17, 1855.

To all whom it may concern:

Be it known that I, O. W. BAYLEY, of Manchester, in the county of Hillsboro and State of New Hampshire, have invented 5 certain new and useful Improvements in the Construction of the Furnaces of Locomotive and other Steam-Boilers, of which the following is a full, clear, and exact description, reference being had to the annexed drawings, making part of this specification, in which—

Figure 1 is an end view of a portion of a locomotive with my improvements attached. Fig. 2 is an isometric view of the same, a 15 portion of the exterior being removed to show the parts within. Fig. 3 is a vertical longitudinal section on the line A A of Figs. 1 and 5; Fig. 4, a section upon the line B B of Fig. 3; Fig. 5, a section upon the line C C 20 of Fig. 3; Fig. 6, a vertical transverse section upon the line D D of Fig. 3.

In the construction of furnaces for steam boilers various plans have been resorted to for the purpose of economizing fuel and for 25 the more perfect combustion of the gases and smoke. Among others, double furnaces have been employed, the compartments of which were alternately supplied with fuel, and the smoke and gases from the one so 30 supplied being permitted to pass up through the fire in the other. It is evident however that the operation of this furnace must be very imperfect, as the fires can only receive one half the amount of oxygen due to the 35 extent of grate surface employed, that which has once passed through the first fire being obliged to descend and pass through the grate of the second one. In other similarly arranged furnaces the smoke from the fresh 40 fire has been thrown into the compartment containing the incandescent fire, and consumed directly upon the surface of this fire. In this case however the gases and heated air are but imperfectly mixed, and the combustion 45 is still defective. In other furnaces the smoke and gases from the fresh fire in one compartment, and the heated air from an incandescent fire in the other compartment, have been thrown into a combustion 50 chamber where they are mixed and consumed together. The performance of these furnaces has not been so satisfactory as was anticipated, owing to the fact, that the smoke and gases from the fresh fire were not suffi- 55 ciently heated, and not so perfectly mixed

with those from the incandescent fire as to burn readily, after they have entered the combustion chamber.

My invention has for its object the removal of all these difficulties, and my furnace differs from those above referred to in this,—that the smoke and gases from the fresh fire are caused to pass through the whole length of the other compartment, and thus become highly heated, and thoroughly 60 mixed with those from the incandescent fire; they then enter together a combustion chamber, where they receive an additional supply of air from a suitable opening, and are consumed immediately behind the tube plate. 65

To enable others skilled in the art to understand my invention I will proceed to describe the manner in which I have carried it out.

The furnace is entirely surrounded by 75 water space F, and is divided into two compartments F, F', by the mid feather or partition G, through the opening H in which, the two compartments communicate with each other. Immediately over the furnace, 80 and separated therefrom by the water space I, is the combustion chamber K, which communicates with the compartments below through the openings L, L'.

M, M', are dampers which slide in the ways a, and are operated by the rods b; by means of these dampers the openings L, L', are closed when necessary. In Fig. 2 the damper M' and the ways a in which it slides, 85 are removed.

N is an opening into the chamber K, through which air is admitted for the more perfect combustion of the unconsumed gases. This opening may be furnished with a door R or other suitable damper or slide, by the 90 partial opening of which the quantity of air admitted is regulated.

O, O', are the fire doors; P, the tube plate; Q, the tubes.

Operation. The fires being started, the fuel in one of the compartments (F) is allowed to become incandescent;—the damper M is then opened and M' is closed;—fresh fuel is then thrown upon the fire in the compartment F', the unconsumed gases and smoke from which pass through the opening H, over the whole length of the incandescent fire in the compartment F, through the opening L into the combustion chamber K;—these gases thus become highly 100 105 110

heated and intimately mixed with those rising from the incandescent fire, and on reaching the combustion chamber they receive a sufficient supply of air through the 5 opening N, to thoroughly consume them;—this takes place immediately in front of the tube plate P. When the compartment F' has ceased to throw off smoke, its damper M', is opened and M, is closed,—fresh fuel 10 is thrown into the compartment F, the smoke from which passes through the opening H, over the fire in F', and through the opening L', into the combustion chamber as before. Fresh fuel is thus added alternately to each compartment of the furnace 15 as the fire in the other becomes incandescent, the dampers being changed as required each time the furnace is fed.

Instead of dividing the furnace into two 20 compartments, a rotating furnace having two or more fire boxes may be employed, each one of which as it revolves receives a fresh feed on arrival at a certain point; the smoke and gases being allowed to pass over 25 the surface of the fire, in all the other chambers, and to issue into a combustion cham-

ber arranged as above; such revolving furnace however forms no part of my present invention and need not be further described.

The above described arrangement and 30 combination of duplicate fire boxes and combustion chamber, is particularly applicable to boilers of locomotives, but may also be applied to boilers of stationary engines. I do not therefore limit myself in its 35 use to locomotive boilers alone, but intend to apply it whenever it may be found useful.

What I claim as my invention and desire to secure by Letters Patent is—

The within described arrangement of the 40 compartments F, F', communicating with each other by the opening H and with the combustion chamber K by the openings L, L', whereby the unconsumed gases from the freshly fed fire are heated by passing 45 over the whole length of the incandescent fire and consumed in the chamber K in the manner substantially as herein set forth.

O. W. BAYLEY.
